(57) **CLAIM**

The ornamental design for a shaving razor package, as shown and described.

DESCRIPTION

FIG. 1 is a front perspective view of a design of a shaving razor package showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is an environmental perspective view thereof.

The dash lines shown illustrate a shaving razor handle and shaving razor cartridges being held by the shaving razor package and form no part of the claimed design.
